UNITED STATES PATENT OFFICE.

CLARK W. PARKER, OF DETROIT, MICHIGAN, ASSIGNOR TO PARKER RUST-PROOF COMPANY OF AMERICA, OF DETROIT, MICHIGAN, A CORPORATION OF MICHIGAN.

TANK.

1,246,991.

Specification of Letters Patent.

Patented Nov. 20, 1917.

Application filed May 5, 1917. Serial No. 166,675.

To all whom it may concern:

Be it known that I, CLARK W. PARKER, a citizen of the United States, and residing at Detroit, in the county of Wayne and State 5 of Michigan, have invented a new and Improved Tank, of which the following is a specification.

This invention relates to tanks in which a constant transverse circulation of all the 10 liquid therein is of importance, and its object is to provide a tank of this character wherein substantially all sediment will be left undisturbed below a false bottom.

This invention consists in a tank having 15 a false bottom, a series of heating pipes positioned in a vertical stack adjacent one side of the tank, and a wall of separated horizontal plates between the stack of heating pipes and the body of the tank. It further 20 consists in bending the lower edges of these horizontal plates toward the pipes in order to form deflectors to cause the heated liquid to circulate freely transversely of the tank. It also consists in an auxiliary bottom for 25 the tank and spaced from the sides thereof below which sediment may accumulate.

In the accompanying drawings, Figure 1 is a perspective of a section of this tank. Fig. 2 is a vertical longitudinal section 30 thereof. Fig. 3 is a vertical transverse section of the tank. Fig. 4 is a detail of the deflecting plates.

Similar reference characters refer to like parts throughout the several views.

The shape and size of the tank and the proportions and details of its parts will depend largely upon the character and amount of the work to be performed. The tank shown in the drawings is particularly adapted 35 for rust-proofing articles of iron and steel according to the process set forth in the patent to Richards, No. 1,069,903, dated August 12th, 1913. In carrying out this process, impurities in the form of iron scale 40 and particles of manganese dioxide often settle on the articles being treated, resulting in specks or spots of untreated or unaffected surface, which areas rust as freely if not more freely than the surfaces of articles 45 which have not been treated at all. By causing a free circulation of hot rust-proofing liquid transversely of the tank while providing for the separation therefrom of the impurities, the time required for the 50 rust-proofing treatment is reduced and the 55

specks or spots of unaffected surface are eliminated.

The tank employed is preferably steel and rectangular, or at least provided with a vertical side 1, an opposite side 2, ends 3 and 4 and a bottom 5 being of any desired contour. As the liquid contents of the tank are to be hot, a lagging 6 of wood or other poor heat conductor and a sheathing 7 of sheet metal, as shown in Fig. 1, may be 60 employed. Reinforcing angles 8 may be secured along the outside of the upper edges of the tank and other angles 9 and 10 may be secured to the inner sides of the tank to act as supports for the cross bars from which 65 are supported the articles to be treated.

A series of steam pipes 12 are mounted adjacent the side 1, water-tight joints being secured by means of the usual nuts 13. A series of upright bars 14 may have outwardly bent upper ends connected to the angle bar 10 and may have short angles 15 to space their lower ends from the side 1 of the tank. The false bottom 16 and its supporting bars 17 may be connected to these 70 bars 14 by means of hinges 18. Any other arrangement which permits the bottom 16 to be moved out of the way may be adopted.

Secured to the bars 14 is an apertured partition, preferably in the form of a series 75 of longitudinal plates 19, having their lower edges 20 bent outwardly toward the pipes 12 in order to constitute deflectors which will project into the ascending heated current of water between the wall 1 and plates 80 19 and direct portions of this current across the tank. These deflectors are therefore at the upper edges of the apertures in the partition. The pipes may be secured to the bars 23 by means of the straps 22 and the bars 23 85 may have inwardly extending upper ends that are secured to the angle bar 10.

The arrows in Fig. 3 indicate the transverse currents of the liquid contents of the tank when steam is turned into the pipes 12. 100 This was determined by suspending small light sheet metal plates from fine wires at many different locations in the tank. This transverse flow is not only at the upper surface of the liquid in the tank but continues 105 to quite near the bottom, where it is reversed and flows toward the heating pipes. It serves to bring fresh liquid to the surfaces of the articles being treated in the tank and thus reduces the time necessary to complete 110

the treatment to a minimum. It also washes away all sediment that may fall on any surface and carries this sediment to the bottom of the tank where the most of it will pass down to the space below the false bottom 5 through the opening between it and the wall 2 of the tank. As the current below the bottom 16 is very slow, the heavy sediment carried into this space will lie there 10 undisturbed until the tank is drained, the false bottom swung up and this sediment removed. Because of the transverse currents in the liquid contents of the tank, the temperature of this liquid will be quite uniform 15 throughout the space between the partition and the side 2.

I claim:—

1. The combination with a tank, of a series of heating pipes mounted above each 20 other adjacent one side of the tank, a series of spaced longitudinal plates mounted parallel to said pipes to constitute an upright partition, and an auxiliary bottom mounted a distance above the bottom of the tank and 25 of less width than the bottom of the tank.

2. The combination of a tank having a vertical side, a series of heating pipes mounted parallel to said vertical side, an apertured partition parallel to said side on the opposite side of said pipes, and a removable auxiliary bottom so mounted in the tank as to 30 leave a chamber beneath it.

3. The combination of a tank, a series of heating pipes mounted adjacent one of the 35 sides of the tank and an apertured partition on the opposite side of the pipes, said partition having a series of inclined deflectors inclining downwardly from the upper edges of the apertures toward said pipes.

4. The combination with a tank having

a vertical side and a horizontal bottom, a vertical series of heating pipes mounted parallel to said side, upright members extending parallel to said pipes, a partition having longitudinal openings secured to said upright members, and an auxiliary floor hinged to 45 said upright members.

5. The combination with a tank having a vertical side and a horizontal bottom, a vertical series of heating pipes mounted parallel 50 to said side, upright members extending parallel to said pipes, a partition having longitudinal openings secured to said upright members, and an auxiliary floor hinged to said upright members, the edge of the auxiliary floor opposite said hinges being spaced 55 apart from the opposite side of the tank.

6. The combination with a tank having a vertical wall, a vertical series of heating pipes mounted parallel to said wall, and a partition formed of horizontal plates on edge and spaced apart, said partition being on the opposite side of said pipes from said wall, the lower edges of said plates being bent 60 toward said pipes.

7. The combination with a tank having a vertical wall, a vertical series of heating pipes mounted parallel to said wall, and a partition formed of horizontal plates on edge and spaced apart, said partition being 70 on the opposite side of said pipes from said wall, the lower edges of said plates being bent toward said pipes, and a removable floor spaced apart from the bottom of the tank and below the lowermost of the plates, 75 the edges of the floor adjacent the pipes and opposite thereto being spaced from the sides of the tank.

CLARK W. PARKER.
